Inventor:

James O'Connor
By ~~McHouiss~~ Atty.

UNITED STATES PATENT OFFICE.

JAMES O'CONNOR, OF NEW YORK, N. Y

MECHANICAL PIANO-PLAYER.

No. 811,082.

Specification of Letters Patent.

Patented Jan. 30, 1908

Application filed February 17, 1904. Serial No. 193,948.

To all whom it may concern:

Be it known that I, JAMES O'CONNOR, a citizen of the United States, and a resident of New York, in the county of New York and State of New York, have invented certain new and useful Improvements in Mechanical Piano-Players, of which the following is a full, clear, and exact specification.

The object of this invention is to provide improved means in connection with mechanical piano-players whereby modulating effects may be obtained at the will of the performer.

Most of the mechanical piano-players referred to are provided with a series of fingers which extend over the piano-keyboard and depress the keys as required by the music. In this invention the tone-modulating effect is obtained by varying the amplitude of movement of these key-fingers, and the mechanism is preferably arranged to operate independently upon predetermined groups or sections of the fingers, so that different modulating effects may be produced coincidently upon the respective sections or ranges of the piano-notes.

The embodiment of this invention shown and described herein shows the range divided into two sections, one comprising the treble or upper register of the piano, while the other comprises the bass or lower register. It is obvious, however, that the range may be divided into any desired number of sections, each provided with its own operating mechanism.

Figure 1 of the drawings is a front view of a portion of a mechanical piano-player with this improved modulating mechanism attached to it, the parts being in their position of rest. Fig. 2 is a side view in section on the line 2-3 of Fig. 1. Fig. 3 is a fragmentary sectional side view also on the line 2-3 of Fig. 1 and shows the position of the parts when one of the bars is operated. Fig. 4 is a fragmentary plan view showing the operating-bars and some of their adjacent parts. Fig. 5 is a fragmentary side view showing a modified arrangement of the device. Fig. 6 is a side view in section, showing a method of operating the modulating devices by pneumatic means.

Referring now to the drawings, 11 represents the front board, 12 the top board, and 13 the cover, of a well-known type of piano-

player, in which the piano-keys 21 are depressed by the outer ends 28 and 29 of the two series of key fingers or levers 26 and 27, the former or short ones engaging the white keys of the piano, while the latter or long ones engage the black keys. The key-fingers 26 and 27 are pivoted, respectively, on rods 30 and 31, and the inner ends of the fingers are engaged on their under sides by the heads 37 of the push-rods 36, each of the latter being connected to an operating-pneumatic 35. The collapsing of the latter raises the inner end of its connected finger 27, thereby depressing the corresponding piano-key and causing it to sound its note in the ordinary manner, the pneumatic-action being controlled in the well-known manner by the passage of a perforated note-sheet over a tracker-bar.

Extending under the inner ends of the series of key-fingers and adjacent to the pneumatic-rod heads 37 are the modulating-bars 51, which, as herein shown, are two in number, one of which is under the key-fingers of the bass or lower register, while the other is under those of the treble or upper register. As these two bars and their operating mechanism are similar, only one of them will be described, it being understood that the action and construction of the other is similar thereto. The bar 51 is mounted for up-and-down movement by providing it at each end with a guide rod or wire 55, which extends downward and is guided in a bearing in the top of the instrument. A nut 56 on the lower end of the rod serves as a stop to limit the upward movement of the bar 51. Journaled in the brackets 61, secured to the top 12, is the rock-shaft 60, which has fixed to it the lifting-arms 62, which are located to engage the under side of the bar 51.

The rock-shaft 60 is provided with an arm 63, fixed to its upper side and pivoted to the connecting-bar 67. The latter extends to and is pivoted on the upper bell-crank lever 70, mounted on the stud 72, which is carried by the bracket 71 on the top 12. The outer end of the bell-crank 70 has pivoted to it the vertical rod 76, the lower end of which is pivoted to the lower bell-crank 77, supported in a stud 78, appurtenant to the front 11 of the instrument. The other end of the bell-crank 77 is connected, by means of the lower rod 81, to one end of the bell-crank 80, pivoted in

the stud 82, also appurtenant to the front 11. To the other end of the bell-crank 80 is pivoted the rod 85, having a knob or key 84 on its upper end and held in a vertical position by the bracket 86, in which it is free to slide. The bracket 86 is secured to the front 11, and these parts are so located as to bring the knob 84 in a convenient position for the hand of the performer. The knob 90 of the treble-
10 keys is similarly located in a convenient position, and if it is desired to further subdivide the range the knobs may all be arranged in a convenient series.

The consecutive operation of the parts is as follows: When the performer desires to modulate the tone in the bass notes, he depresses the knob 84, thus operating the rock-shaft 60 by means of its connections with the knob, thereby lifting the bar 51 by means of
15 the two arms 62, which engage the bar on its under side. Lifting the bar 51 raises the inner ends 33 of all the key-fingers of the lower register, thereby lowering the outer ends 28 and 29 of the key-fingers and causing them to
20 partially depress their corresponding piano-keys, as shown in Fig. 3. The extent of this depression is not enough to sound the keys. If, therefore, any one of the keys is depressed to its sounding position (shown by the dotted-and-dash line 23) by the operation of its pneumatic 35, the blow struck upon the piano-key 21 will be a comparatively light one, owing to the reduced amount of movement necessary to complete the stroke, thus producing a
30 modulation of the tone, the degree of which depends on the extent of depression of the knob 84. If the performer wishes to still further modulate the tone, he depresses the knob 84 a little more, or if he wishes to increase
35 the sound he allows the knob to raise a little. In this way the degree of modulation may be varied at will by the simple manipulation of the knob 84. If it is desired to modulate the tone in the upper register or
40 treble, the knob 90 will be depressed instead of the knob 84, or both knobs may be depressed if the whole range is to be affected. The extent of these depressions will control the degree of modulation produced, and this
45 degree of modulation may be independently varied in both sections of the piano-register, thus enabling the performer to produce different effects coincidently upon the respective sections or ranges of the piano-notes. As
50 soon as the knob 84 or 90 is released the parts under its control will be returned to their position of rest by the downward pressure of the inner ends 33 of the key-fingers.

In Fig. 5 is shown a modified method of varying the amplitude of movement of the key-fingers by varying the stroke of the motor which moves those fingers. In this modification the modulating-bar 40 is applied to any convenient portion of the operating-rods 41 or to the movable leaf 42 of the pneumatic
65

motor 43, the rod or the leaf being provided with suitable abutments 44 for coöperating with the bars. The bars are pivotally mounted on a shaft or pivots 45, journaled in bearings appurtenant to the frame of the instrument, the bar being operated by means of an arm 47, provided with a rod 48, practically corresponding with the rod 67 of the other figures. The modulating-bar 40 by its position controls the extent of downward movement of the operating-rods 41 or the movable leaf of the bellows-motor, as the case may be, and by shifting the modulating-bar the effective stroke of the motors is correspondingly varied. In this modification, as in that previously described, the series of operating-rods 36 may be subdivided in any desired way or to any desired extent, so as to control the different sections independently each by its own operating knob or key.

In the modified construction shown in Fig. 6 pneumatic means are used for operating the modulating devices. The knob 96 is mounted on a stem 97, which passes through the top 12 of the instrument. The lower end 90 of the stem 97 is pivoted to the valve 95, which controls the pneumatic primary devices 94 of a well-known type, connected, by means of the tube 99, to the motor-bellows 98. The latter is provided with a connecting-rod 92, 95 the upper end of which is pivoted on the modulating-bar 91, which is mounted at each end on a bracket 93 by means of a pivot 88. A check-nut 87 on the connecting-rod 92 limits the upward swing of the modulating-bar 100 91. A spring 89 is provided which tends to keep the valve 95 closed and to hold the knob 96 in its upper position. In the operation of these parts the knob 96 is depressed, thereby opening the valve 95 and permitting the primary devices 94 to operate, and thus cause the bellows 98 to collapse. This raises the connecting-rod 92, thereby swinging the modulating-bar 95 upward, thus raising the ends 105 of the key-fingers 33 and causing them to correspondingly depress their associated piano-keys. The modulating-bar 91 may also be made to operate directly upon the operating-rods 41 in a manner similar to that shown in Fig. 5.

Each key-finger is preferably provided with an adjusting-screw 34 in order to furnish means for independently adjusting the key-fingers to aline them or to cause them to produce the same effect on their respective piano-keys when the universal bar 51 is operated. By turning the screw the zone of movement of each key-finger may be altered to bring the finger into conformity with the other fingers of the set.

The various terms herein employed to denote position and direction are employed in their relative and not their absolute sense.

In many ways which will be obvious to those familiar with this art the devices here- 130

in shown may be further modified in position, direction, and degree to suit different types of instruments or different conditions of service.

I claim as my invention—

- 5 1. In a mechanical piano-player, the combination with automatic devices for selectively operating the key-fingers, of means for moving the key-fingers a portion of their stroke in advance of the action of the automatic devices.
- 10 2. In a mechanical piano-player, the combination with automatic devices for selectively operating the key-fingers, of means for moving a predetermined section of the key-fingers a portion of their stroke in advance of the action of the automatic devices.
- 15 3. In a mechanical piano-player, the combination with automatic devices for selectively operating the key-fingers, of means for independently moving predetermined key-fingers a portion of their stroke in advance of the action of the automatic devices.
- 20 4. In a mechanical piano-player, the combination with a series of key-fingers, of a plurality of bars, each adapted to engage a predetermined number of the key-fingers to move them a portion of their stroke, and means for independently operating each bar.
- 25 5. In a mechanical piano-player, the combination with a series of key-fingers, of a plurality of bars, each adapted to engage a predetermined portion of the key-fingers to move them simultaneously a portion of their stroke,

and means convenient to the hand of the performer for operating the bars independently. 35

6. In a mechanical piano-player, the combination of means for varying the amplitude of movement of the key-fingers to modify their effect on the piano-keys, and means for independently adjusting the zone of movement of the individual key-fingers. 40

7. In a mechanical piano-player, the combination, with a series of key-fingers, of a plurality of bars each mounted in operative relation to a predetermined set or section of the fingers, and a series of adjusting-screws for independently adjusting the zone of movement of the individual key-fingers. 45

8. In a mechanical piano-player, the combination with a series of key-fingers, of a plurality of bars each mounted in operative relation to a predetermined set or section of the key-fingers, a series of adjusting-screws for independently adjusting the zone of movement of the individual key-fingers, and means 50 for independently operating each bar to vary the amplitude of movement of the keys of the respective sections. 55

In testimony whereof I have signed my name to this specification in the presence of 60 two subscribing witnesses.

JAMES O'CONNOR.
